(57) **CLAIM**

The ornamental design for a cup handle, as shown and described.

DESCRIPTION

FIG. 1 is a front, perspective view of a cup handle showing our new design;

FIG. 2 is a front view thereof;

FIG. 3 is a rear view thereof;

FIG. 4 is a right side view thereof, the left side view being a mirror image of the right side view;

FIG. 5 is a top view thereof; and

FIG. 6 is a bottom view.

FIG. 7 is a front, perspective view of the cup handle of FIG. 1 showing our new design with additional environmental subject matter;

FIG. 8 is a front view thereof;

FIG. 9 is a rear view thereof;

FIG. 10 is a right side view thereof, the left side view being a mirror image of the right side view;

FIG. 11 is a top view thereof; and,

FIG. 12 is a bottom view.

The features shown in broken lines are environmental subject matter to the cup handle or portions of the cup handle forming no part of the claimed design. The features shown in long dash-short dash bolded broken lines indicate the bounds of the claimed design and otherwise form no part of the claimed design.
